UNITED STATES PATENT OFFICE.

JAMES R. CARDWELL, OF CHICAGO, ILLINOIS.

WALLET.

1,088,059.

Specification of Letters Patent. Patented Feb. 24, 1914.

Application filed May 11, 1910. Serial No. 560,556.

To all whom it may concern:

Be it known that I, JAMES R. CARDWELL, citizen of the United States, residing at Chicago, in the county of Cook and State of Illinois, have invented a certain new and useful Improvement in Wallets, of which the following is a full, clear, concise, and exact description, reference being had to the accompanying drawings, forming a part of this specification.

My invention relates to wallets, and has for its object the construction of a very simple form of wallet and which is adapted to contain paper money within small compass.

In practising my invention, I employ a sheet of some suitable material, preferably leather, approximating in superficial area the size of a bank note, which sheet of leather I preferably crease along two lines, one extending longitudinally of the sheet and dividing the same into two equal parts and the other extending transversely of the sheet and dividing the same into two equal parts, the four lines together dividing the sheet into four equal parts. In securing the bank notes within the wallet, the wallet is opened flat, the bank notes are laid thereupon and the wallet is then folded along its creases so that the bank notes are creased similarly to the wallet and are held within the folds of the wallet.

In order positively to insure the retention of the bank notes within the wallet, I project a wing from one of the quarters of the sheet, which may overlie the bank notes and is inclosed within the wallet when folded. A second wing may also be projected from another quarter of the main wallet sheet for a similar purpose. The projecting wings preferably have sufficiently resilient connection with the main wallet sheet as to cause said wings to move toward the main wallet sheet when they are released after they have been turned back. These wings therefore do not require much manipulation to permit bills or notes to be tucked between the same and the main wallet sheet, the wings automatically acquiring and retaining the position they should occupy in order properly to be interfolded.

In order to facilitate the folding of the wallet, the material composing the main sheet of the wallet is discontinued just where the longitudinal and transverse creases intersect, so that said material will

not buckle and bunch at this intersection, which result is preferably accomplished by entirely removing the material so that there is a distinct aperture or opening through the main sheet of the wallet where the creases thereof intersect. This opening desirably extends along or in alinement with one folding line and laterally across that half of the wallet sheet that is inclosed by the remaining half of the wallet sheet, so as to enable the wallet to hold more bank notes than it would if the inclosed half of the wallet sheet did not have material removed at the location indicated.

I will explain my invention more fully by reference to the accompanying drawings showing the preferred embodiment thereof, and in which—

Figure 1 is a view of the wallet opened flat with the bank note receiving side of the wallet opened to view, a bank note being indicated in position in dotted lines; Fig. 2 is a reverse view of the wallet opened flat; Fig. 3 is a view of the wallet partially folded; Fig. 4 is a view of the wallet completely folded; and Fig. 5 is a sectional view on line 5-5 of Fig. 3.

Like parts are indicated by similar characters of reference throughout the different views.

The wallet comprises, in the preferred embodiment of the invention, a substantially flat main sheet *a* which approximates in superficial area of a bank note, said main sheet having projecting therefrom a pair of wings *b*, these wings being joined with that half of the main wallet sheet that is to be interfolded by the remaining or infolding half of the wallet sheet. The main sheet of the wallet has a longitudinal crease *c* dividing the wallet longitudinally into two equal parts, and a transverse crease *d* dividing the infolding half of the main wallet sheet into two substantially equal parts. The wings *b* are shown as being attached to the main wallet sheet along the outer longitudinal edge of the infolded half of such sheet, and in order that these wings may have a natural tendency to lie close to the main wallet sheet, they are laid flat thereupon and stitches *b'* are passed through portions thereof and portions of the main wallet sheet that are in flat face engagement. In this way, the connections between the wings and the main sheet are sufficiently resilient to cause said wings to move toward the

main sheet when they are released after having been turned back, whereby said wings are easily positioned to permit bank notes to be tucked thereunder and which 5 wings are somewhat automatically repositioned to permit them to be interfolded.

I discontinue the material of the main sheet where the folding lines *c* and *d* intersect, to which end an aperture or opening *f* 10 is preferably formed clear through the wallet, this opening desirably extending in alinement with the transverse folding line and laterally across that half of the wallet sheet that is inclosed by the remaining half 15 of the wallet sheet to divide one-half of the wallet sheet itself into two wings, so as to enable the wallet to hold more bank notes than it would if the inclosed half of the wallet sheet did not have material removed 20 at the location indicated. The wings *b* are secured to the outer longitudinal edges of the wings formed in the main wallet sheet by the slot *f*.

In using the wallet, it is opened flat as 25 indicated in Fig. 1, the bank notes are inserted between the wings and the main wallet sheet, as indicated at *g* in dotted lines, whereafter the wallet may be preferably folded along the crease *c* to crease the bank 30 notes along a line substantially coinciding with the crease *c*, this fold of the wallet being indicated in Fig. 3. After the wallet has thus been folded, it is folded along its remaining crease *d*, so that the bank notes 35 are creased along a line coinciding with the crease *d*. It will be seen that the bank notes are thus thoroughly interfolded within the wallet and are not removable from the wallet until the wallet is unfolded.

40 A flap *h* may be continued from one end of the infolding half of the main wallet sheet to overlie the free ends of the folded wallet, a fastener having its members *i* disposed upon the wallet sheet and flap so as 45 to be adapted for interlocking engagement to hold the flap in position. A securing

chain or string may be attached to the wallet by means of the eyelet *k* passing through the wallet.

Having thus described my invention, I 50 claim as new and desire to secure by Letters Patent the following:

1. A wallet comprising a rectangular sheet of suitable wallet material provided with longitudinal and transverse folding 55 lines intersecting at substantially the center of the sheet and having the material removed along said transverse folding line from the said point of intersection to an edge of said sheet, and means located along 60 a longitudinal edge of the said sheet to embrace and retain in position bank-notes disposed on the said sheet when the wallet is open.

2. A wallet comprising a main portion 65 consisting of a rectangular sheet provided with a transverse folding line across its middle and having a longitudinal dimension approximately the length of a bank-note and a transverse dimension approximately 70 one-half the width of a bank-note, said sheet being provided at one side with a pair of outwardly extending wings disposed on opposite sides of said folding line, said wings and said main portion being adapted to receive one or more bank-notes thereon whereby the wings and bank-notes may first be folded over onto the said main portion and the said main portion and bank-notes then 75 folded on said transverse folding line to inclose the bank-notes and wings within the wallet, and means secured to the said wings for holding the bank-notes in position upon the wings and the main portion when the wallet is open.

In witness whereof, I hereunto subscribe my name this 9th day of May A. D., 1910.

JAMES R. CARDWELL.
